Invention

George J. Maas
By H. G. Underwood
Attorney

UNITED STATES PATENT OFFICE.

GEORGE J. MAAS, OF NEGAUNEE, MICHIGAN.

PIPE-JACK.

SPECIFICATION forming part of Letters Patent No. 694,899, dated March 4, 1902.

Application filed December 16, 1901. Serial No. 86,176. (No model.)

To all whom it may concern:

Be it known that I, GEORGE J. MAAS, a citizen of the United States, and a resident of Negaunee, in the county of Marquette and State 5 of Michigan, have invented certain new and useful Improvements in Pipe-Jacks; and I do hereby declare that the following is a full, clear, and exact description thereof.

My invention has especial reference to jack-screws for pulling pipes from the ground into which they have been driven; and it consists in certain peculiarities of construction and combination of parts, as will be fully set forth hereinafter in connection with the accompanying drawings and subsequently claimed.

In the said drawings, Figure 1 is a vertical central sectional view of my improved pipe-jack, showing also a pipe to be extracted thereby; and Fig. 2 is a broken plan view 20 with the said pipe in section on the line 2 2 of Fig. 1.

Referring to the drawings, *a* represents a suitable base supporting a hollow post *b*, preferably formed integrally therewith, which 25 post is formed, preferably at its upper end, with an interiorly-screw-threaded portion *c* for engagement with the exterior threads of a hollow jack-screw *d*. This jack-screw is formed with a cap *e*, having peripheral recesses for the reception of the ends of bars *ff* and an annular groove in its upper face for receiving a ring *g* of hardened metal, said ring having an annular groove in its upper face for the reception of antifriction balls or 30 rollers *hh*. Above the cap *e* is a clamp-ring *i*, having an annular recess in its under surface fitted with an annular wear-plate *j* of hardened metal, which rests on the balls *hh*, as shown in Fig. 1. This ring *i* has a beveled bore, and clamping-wedges *k* are provided, so that when the jack-screw is set over and around a pipe *m*, projecting from the ground, these wedges *k* are forced between the pipe and the inner wall of the clamp-ring *i*, 35 thereby firmly holding the pipe to the clamp-ring by frictional contact. The said clamp-ring is formed with peripheral recesses for the reception of bars *nn*.

The operation of my device will be readily 40 understood from the foregoing description of its construction, taken in connection with the accompanying drawings. In order to loosen

the hold of the pipe *m* in the ground, heavy pressure is brought to bear on the pipe, so as to turn it partially by means of the clamp-bars *n* *n*, which bars serve also to shake the pipe back and forth, and then by manning one or more of the lower bars *ff* and walking around the pipe in the manner of operating a capstan the jack-screw *d* is raised, carrying with it the clamp-ring *i* and the pipe *m*, clamped thereto, as described, so that the pipe is very quickly and readily pulled from the ground with the expenditure of but little force. 55

Having thus described my invention, what I claim as new, and desire to secure by Letters Patent, is—

1. In a pipe-jack, the combination with a suitable base and a hollow interiorly-threaded 70 post supported thereby, of a hollow jack-screw in movable engagement with said post, and a pipe-clamping device supported by said jack-screw.

2. In a pipe-jack, the combination with a 75 suitable base and a hollow interiorly-threaded post supported thereby, of a hollow jack-screw in movable engagement with said post, and a pipe-clamping device located above said jack-screw, and kept from contact therewith by 80 interposed antifriction balls or rollers.

3. In a pipe-jack, the combination with a suitable base and a hollow interiorly-threaded post supported thereby, of a hollow jack-screw in movable engagement with said post, and 85 provided with a cap at its upper end, a clamp-ring supported by said cap; and wedges for clamping said clamp-ring to a pipe projecting therethrough.

4. In a pipe-jack, the combination with a 90 suitable base, and a hollow interiorly-threaded post supported thereby, of a hollow jack-screw in movable engagement with said post; a flanged cap at the upper end of said jack-screw; bars projecting laterally from said cap; 95 antifriction balls or rollers resting in a groove in the upper face of said cap; a clamp-ring resting on said balls or rollers and formed with a beveled bore; bars projecting laterally from said clamp-ring; and wedges for clamping said clamp-ring to a pipe projecting therethrough. 100

5. In a pipe-jack, a hollow open-ended post adapted to be set over and around a pipe pro-

jecting from the ground; a tubular jack in vertical movable engagement with said post, and a pipe-clamping device supported by said tubular jack, whereby, as the latter is elevated the clamping device is raised therewith, and the attached pipe drawn from the ground.

6. In a pipe-jack, a hollow open-ended post adapted to be set over and around a pipe projecting from the ground; a tubular jack supported within and in vertical movable engagement with said post; a clamp-ring supported by said tubular jack and surrounding said pipe; wedges for clamping said ring to the said pipe; and bars projecting from said

clamp-ring, whereby the said pipe may be turned or shaken loose, by the rotary movement of said clamp-ring, and drawn from the ground as the clamp-ring is elevated by the upward vertical movement of the tubular jack.

In testimony that I claim the foregoing I have hereunto set my hand, at Negaunee, in the county of Marquette and State of Michigan, in the presence of two witnesses.

GEORGE J. MAAS.
